UNITED STATES PATENT OFFICE

142,814

DESIGN FOR A MACHINE TOOL UNIT

Walter D. Archea and Norman H. Doane, Cincinnati, Ohio, assignors to The Cincinnati Milling Machine Co., Cincinnati, Ohio, a corporation of Ohio

Application November 26, 1943, Serial No. 111,792

Term of patent 14 years

(Cl. D54—14)

To all whom it may concern:

Be it known that we, Walter D. Archea and Norman H. Doane, both citizens of the United States, residing at Cincinnati, in the county of Hamilton and State of Ohio, have invented a new, original, and ornamental Design for a Machine Tool Unit, of which the following is a specification, reference being had to the accompanying drawings, forming part thereof.

Figure 1 is a front elevation of a machine tool unit showing our new design.

Figure 2 is a plan view of the unit shown in Figure 1.

Figure 3 is a side elevation of the unit shown in Figure 1 as viewed from the right side thereof.

Figure 4 is a side elevation of the unit shown in Figure 1 as viewed from the left side thereof.

We claim:

The ornamental design for a machine tool unit, as shown.

WALTER D. ARCHEA.
NORMAN H. DOANE.
